UNITED STATES PATENT OFFICE.

MORRIS WEINTRAUB, OF NEW YORK, N. Y.

DESIGN FOR A TEAPOT, COFFEE-POT, OR SIMILAR ARTICLE.

41,765.

Specification for Design. Patented Sept. 12, 1911.

Application filed May 19, 1911. Serial No. 628,247. Term of patent 7 years.

To all whom it may concern:

Be it known that I, MORRIS WEINTRAUB, a citizen of the United States, residing in the city of New York, borough of Manhattan, in the county and State of New York, have invented a new, original, and ornamental Design for a Teapot, Coffee-Pot, or Similar Article, of which the following is a specification, reference being had to the accompanying drawing, forming part thereof.

Figures 1 and 2 are elevations of opposite sides of a teapot showing my design.

I claim:

The ornamental design for a tea pot, coffee pot or similar article as shown.

MORRIS WEINTRAUB.

Witnesses:

THEO. G. HOSTER,
CHARLES ROTHOLZ.
